UNITED STATES PATENT OFFICE.

DAVID J. SEAMAN, OF SOUTH BEND, INDIANA.

DESIGN FOR FABRIC.

SPECIFICATION forming part of Design No. 34,600, dated May 28, 1901.

Application filed May 6, 1901. Serial No. 59,056. Term of patent 14 years.

To all whom it may concern:

Be it known that I, DAVID J. SEAMAN, a citizen of the United States of America, residing at South Bend, in the county of St. Joseph and State of Indiana, have invented and produced a new and original Design for Fabrics, of which the following is a specification, reference being had to the accompanying drawing, forming a part hereof.

This design relates to the ornamentation of cotton, silk, woolen, paper, celluloid, and other fabrics.

In the drawing I have shown a plan view of the design.

The leading feature of the design resides in the representation of festoons formed of holly leaves and berries and having sprays of the same elements rising from their upper sides. The festoons A are formed from con-

tinuous streamers of holly leaves and berries 20 and have their ends caught and held by bows B of ribbon. From the upper sides of the festoons sprays C spring upward and approach each other, and between these sprays are stars D. Between the festoons are sprays 25 or bunches of holly leaves and berries E, and clusters of bells F depend from the alternate bows B.

What I claim is—

The design for a fabric herein described 30 and shown.

In testimony whereof I have signed this specification in the presence of two attesting witnesses.

DAVID J. SEAMAN.

Witnesses:

CLARA B. SHULTZ,
E. T. HOUSEKEEPER.
